Specification for Design.

Patented Oct. 7, 1919.

Application filed June 20, 1919. Serial No. 305,668. Term of patent 14 years.

To all whom it may concern:

Be it known that I, CAP B. COLLINS, a citizen of the United States, residing in Oak Park, in the county of Cook and State of Illinois, have invented a new, original, and ornamental Design for Razor-Blades, of which the following is a specification, reference being had to the accompanying drawing, forming part thereof.

The figure of the drawing is a face view of the razor-blade showing the new design.

I claim:

The original design for a razor-blade as shown.

CAP B. COLLINS.
